UNITED STATES PATENT OFFICE.

TARGE G. MANDT, OF STOUGHTON, WISCONSIN.

DESIGN FOR A BOLSTER-PLATE FOR VEHICLES.

SPECIFICATION forming part of Design No. 35,106, dated September 17, 1901.

Application filed August 10, 1901. Serial No. 71,661. Term of patent 7 years.

To all whom it may concern:

Be it known that I, TARGE G. MANDT, a citizen of the United States, residing at Stoughton, in the county of Dane and State of Wisconsin, have invented and produced a new and useful Design for Bolster-Plates for Vehicles, of which the following is a specification.

My invention relates to a new and useful design for bolster-plates for vehicles, of which the following is a specification, reference being had to the accompanying drawings, forming a part thereof, in which—

Figure 1 is a plan view of my plate. Fig. 2 is a side view of the same. Fig. 3 is an end view of the same.

Like numerals of reference designate like parts in the different views of the drawings.

The numeral 1 designates the body of my plate, which is substantially plane. The ends 2 of the body are straight and parallel, but the sides 3 are cut away to form double reverse curves, each comprising a long arc 3^a intermediate two oppositely-curved shorter

arcs 3^b . Formed on the corners of the plate are downturned lugs 4, which form legs which extend at right angles to the plane of the body 1. The body 1 is centrally apertured at 5, which aperture is surrounded by a boss 6. Smaller apertures 7 pierce the ends, and an inwardly-turned hook 8 is formed centrally the arc 3^a on one side.

The essential or material features of my design are the plane body having a raised boss 6, downturned legs 4, straight ends, curved sides, and a hook 8 centrally one side.

Having described my invention, what I claim as new, and wish to secure by Letters Patent, is—

The design for a bolster-plate for vehicles, substantially as shown and described.

In testimony whereof I have hereunto set my hand in presence of two subscribing witnesses.

TARGE G. MANDT.
